UNITED STATES PATENT OFFICE

GEORGE W. KING, OF COFFEYVILLE, KANSAS, ASSIGNOR OF THREE-FOURTHS TO ROY T. OSBORN, OF BRONXVILLE, NEW YORK

OIL STILL

Application filed October 1, 1928. Serial No. 309,599.

My invention relates more particularly to oil stills of the kind commonly employed for straight distillation, cracking, etc., in which the bulk of oil to be treated is charged into a boiler or still proper, arranged in a suitable furnace and heated therein until the desired amount of the lighter components of the oil has been distilled off. The invention is applicable to such stills, whether employed for topping, cracking or other purposes, and is of particular advantage in connection with stills employed for running to coke or substantially thereto.

Ordinarily, the still proper or boiler is in the nature of a large steel cylinder with closed ends and mounted in the furnace setting with its axis horizontal, and I have exemplified my invention in connection with a still of this character. After a run has been completed, there remains in the bottom of the still a bed of coke containing more or less other solids and, depending on the extent to which the distillation is carried, an overlying body of heavy, tarry material, and it is the common practice for workmen to enter the still after it has cooled down through a manhole provided in the end of the shell, and to shovel coke, etc. out through the manhole so that the shell may be practically empty and clean before it is again charged with oil to be distilled. The shell is ordinarily provided with a suction and charging line entering through the top of the shell and extending nearly to the bottom thereof. This line is ordinarily used for charging the still with oil but is sometimes used, with an appropriate suction pump, for removing oil or tar therefrom. In order to permit the workmen to properly and conveniently clean out the still, it has been the practice to make the lower end of the suction and charging line within the still of a separate section, providing such section and the lower end of the main portion of the charging line with flanges, drilled with a number of holes, by means of which the lower removable section of the line can be secured to and released from the lower end of the main line.

Before the cleaning out operation, the low-

er detachable section is removed from the shell after releasing the bolts by which it is secured to the main section of the charging and suction line and, after the cleaning operation is completed, the removable line section is again bolted to the main lower end of the suction and charging line. In ordinary practice, the still shell is of a diameter of 12 to 14 feet and the removable section is about 6 feet long, 6 inches in diameter and weighs considerably over 100 pounds. When this pipe section is being attached or detached, the operation requires, in addition to the workman manipulating the bolts, a second workman to hold the removable section in position until completely detached or attached, as the case may be. The time required for this operation is quite considerable, putting a great strain on the workman holding the removable section in position and it has frequently happened that the workman has dropped the pipe and, in many instances, been seriously injured thereby.

It is the purpose of the present invention to so connect the detachable section to the main section of the charging line that a single workman can manipulate the detachable section to remove it out of the way of the operatives who are to clean out the still and to dispense with the services of the second workman and obviate the dangers above-mentioned. With this object in view, instead of forming the lower section completely detachable, I hinge it to the main section of the charging and suction line and provide means whereby it may be swung up out of the way of those engaged in cleaning out the still and securely anchored until the cleaning operation is completed and then readily returned to operative position and secured therein. Other more specific features of my invention will appear from the drawing and the detailed description below.

In the drawing accompanying and forming a part of this specification, Fig. 1 is a vertical axial section through a shell of a still to which my invention has been applied; Fig. 2 is an enlarged fragmentary view, in side elevation, of the meeting ends of the two sections of the

charging and suction pipe; Figs. 3 and 4 are plan views of details.

Referring to Fig. 1 of the drawing, the shell of the still is shown at 2 and the manholes with their removable cover plates at 3 and 4. It has not been thought essential to illustrate either the furnace setting or the condensation apparatus, as they may be of any usual or preferred type. The lower end of the vapor line is shown at 5.

The lower end of the main or stationary portion of the discharge and suction pipe is shown at 6 and the lower end thereof, within the still, is formed or provided with a flange 7, drilled at suitable intervals as at 8 for the reception of bolts. The flange is also formed with a lug or ear 9, perforated at 10 for a purpose which will appear. The movable section 11 of the suction and charging pipe is formed or provided at its upper end with a corresponding perforated flange 12, from which extends a pair of lugs 13. These lugs are perforated as at 14. The lugs 13 are spaced apart, as best shown in Fig. 4, to receive between them the lug 9 on the flange on the lower end of the main section of the charging and suction line and a bolt or pin 15 extends through the perforations in the lugs of the respective flanges so that the movable section 11 is hinged to the stationary section of the suction and charging line.

When the still is being operated, the two flanges are firmly united by bolts 16 extending therethrough and provided with suitable nuts. A chain 17, which may be in the form of a loop, is so located and secured to the shell that, when the movable line section is swung up to substantially horizontal position, as shown in dotted lines in Fig. 1, it may be received in the loop and thus held out of the way of the workmen employed in cleaning out the shell.

After a run, a single workman enters the shell, releases the bolts and swings the movable line section up to horizontal position and places the chain loop about the end thereof. After the cleaning operation is completed, the end of the movable section is released from the loop, and the section is dropped to vertical position, in which the flange on the upper end thereof is in contact with the flange of the lower end of the stationary section of the charging and suction line, and the securing bolts are then replaced so that the structure is in condition for operation.

I claim:

1. In an apparatus of the class described, a still shell, a charging and suction line extending into the shell, a flange on the lower end of said line having a lug thereon, a movable line section having a flange and lugs on the upper end thereof, a pin extending through the lugs and removable bolts extending through the flanges and holding them in fixed relation.

2. In an apparatus of the class described, a still shell, a charging and suction line extending into the shell through the top thereof, a movable pipe section hinged to the lower end of the line, and means for securing the movable pipe section rigidly with respect to said charging and suction line.

3. In an apparatus of the class described, a still shell, a charging and suction line extending into the shell through the top thereof, a movable pipe section hinged to the lower end of said line, means for rigidly securing said pipe section with respect to said line, and means for retaining the pipe section in elevated position.

In testimony whereof, I have subscribed my name.

GEORGE W. KING.
